Inventor.

United States Patent Office.

GEORGE W. PRENTICE, OF WHITINSVILLE, MASSACHUSETTS.

Letters Patent No. 96,835, dated November 16, 1869.

IMPROVEMENT IN MECHANISM FOR RAISING TOP-ROLLER WEIGHTS IN SPINNING-MACHINES.

The Schedule referred to in these Letters Patent and making part of the same.

To all whom it may concern:

Be it known that I, GEORGE W. PRENTICE, of Whitinsville, in the county of Worcester, State of Massachusetts, have invented certain new and useful Improvements in Mechanism for Raising Top-Roll Weights, &c., of Spinning and Drawing-Frames, and for similar purposes; and I do hereby declare the following to be a full, clear, and exact description of the same, reference being had to the accompanying drawings, in which—

Figure 1 shows a side view of my invention, and

Figure 2 is a plan of its arrangement, with the levers and weights.

The same letters denote the same parts in both.

A A are the rods depending from the saddles, and passing through the levers B B, on which are hung the weights C C, in the usual way.

D is a slide, bolted to the frame H by its flange E, and supporting the standard F, which is adjustable on it by the screw g, the standard F having a slot in which is pivoted the cam-lever H, and in which the bridge I plays, and another one at right angles to the first, in which the arms or lugs of the bridge play, and by which it is guided.

The bridge I is made to move freely in the standard, and be kept in place horizontally by its arms i i, and has notches to receive the levers B B.

The lever H has a cam or arm, so formed and arranged that by lifting it to the position shown at H', it will raise the weights, by means of the bridge I and

levers B B, sufficiently to relieve the rods A A and allow the rolls to be removed, and its form is such that its point passes a little over beyond a perpendicular line drawn through its pivot, and thus supports the bridge and retains it in position, until it is pressed down again, and when down, as at H, it leaves the weights and levers free to operate as usual.

The slide D allows the position of the standard F to be changed, so that it can be placed where it will operate best, and also permits the flange E to be bolted to the frame K, between other pieces, which otherwise might be in the way of the standard.

It will be seen that my invention contains within itself a principle of support of its parts in position, without the aid of catches or other devices, and is, to that extent, self-operating.

What I claim as new, and desire to secure by Letters Patent, is—

1. In combination with the bridge I, or other equivalent device for holding the weight-levers B, the cam-lever H, arranged to raise the weights, and to support them of itself, when raised, by the position it then assumes, substantially as described.

2. In combination with the lever H, the bridge I and adjustable standard F, constructed and arranged substantially as described.

G. W. PRENTICE.
